UNITED STATES PATENT OFFICE.

RUFUS M. SHERROD, OF DYERSBURG, TENNESSEE, ASSIGNOR OF FORTY-NINE ONE-HUNDREDTHS TO BYNUM H. SULLINGER, OF DYERSBURG, TENNESSEE.

POOL-BALL CARRIER.

Application filed March 27, 1922. Serial No. 547,040.

To all whom it may concern:

Be it known that I, RUFUS M. SHERROD, a citizen of the United States, residing at Dyersburg, in the county of Dyer and State 5 of Tennessee, have invented certain new and useful Improvements in Pool-Ball Carriers, of which the following is a specification, reference being had to the accompanying drawings.

10 This invention relates to improvements in pool ball carriers, and more particularly to a device for use in transporting pool balls from the rack in which they are stored during a game to the pool table.

15 An important object of the invention is to provide a device of this character which will receive the balls directly from the rack and which may be employed in conjunction with the racks now in use with very slight 20 changes or modifications of the structures thereof.

25 A further object of the invention is to provide a device of this character which may be manipulated with one hand so that the other hand of the user may be employed for moving the balls from the rack into the receptacle.

30 A still further object of the invention is to provide a device of this character whereby the balls are maintained in a substantially horizontal path during their passage from the rack into the container in order that they may not be broken by falling thereof.

35 These and other objects I attain by the construction and arrangement shown in the accompanying drawings wherein for the purpose of illustration is shown a preferred embodiment of the invention and wherein like reference characters designate like parts throughout:

40 In the drawings:

Figure 1 is a sectional view showing an apparatus constructed in accordance with my invention in position to receive the balls 45 from a pool rack;

Figure 2 is a side elevation of the device; and

Figure 3 is an end elevation thereof.

50 Referring now more particularly to the drawings, the numeral 10 indicates cylinders, two in number, and arranged in substantially parallel relation, the cylinders being spaced and braced by interposed securing and bracing elements 11. One end of each of the cylinders 10 is closed, as indi-

cated at 12, and the opposite end thereof is provided at that portion remote from the other cylinder 10 with a projecting flange or hood 13.

55 The numeral 14 designates a handle member having its legs secured to the cylinders 10 at a point adjacent the open end of the cylinders, and the numeral 15 designates an arm loop having its ends secured to the cylinders adjacent the closed end thereof or between the handle member 14 and this closed end. In the use of the device the loop 15 is adapted for the insertion of the arm, the hand grasping the handle 14 so that the open end of the cylinders may be positioned as 60 desired.

65 As is well known to those familiar with the art, pool-ball racks are broadly divided into two classes, each of which is provided with shelves 16 and an end wall 17 maintaining the shelves in proper spaced relation. In one of these classes the end walls are provided with openings 18 through which the balls carried by the shelf may be removed. 70 In accordance with my invention racks 75 which are not provided with such openings would have the openings formed therein so that the end flanges 13 of the cylinders may be engaged in the openings and the balls moved from the rack by the hand into the 80 cylinders 10. As hereinbefore stated, the arm is inserted through the loop 15 and the hand engaged with the handle 14 and while the device is thus held, the ends of the cylinders are moved into position at the openings 85 so that the cylinders 10 align with an adjacent pair of such openings. The balls from the shelves 16 are then moved with the other hand into the cylinders by means of which they may be transported to the table. This 90 structure is particularly well adapted for use in this connection by reason of the fact that in placing the balls in the racks they are usually placed upon adjacent shelves and accordingly single positioning of the device 95 will ordinarily suffice for removing all the balls from the rack R. The cylinders on the side thereof remote from the handle 14 and arm loop 15 may be connected by a bracing strap 19 disposed adjacent the open end of 100 the cylinders and which will serve as means for hanging up the implement when not in use.

105 From the foregoing it is believed to be obvious that a device constructed in accordance with my invention is particularly well 110

adapted for the use for which it is intended by reason of the fact that it prevents drop-page and breakage of the pool balls and that it renders the operation of removing the 5 balls from the rack to the table a very simple matter. It will likewise be obvious that the construction as hereinbefore set forth is capable of some change and modification without materially departing from the spirit 10 of my invention and I accordingly do not limit myself thereto except as hereinafter claimed.

I claim:

1. A pool ball carrier for use in transferring pool balls from wall racks having supporting shelves and an end wall with which the shelves are engaged and which is provided with openings aligned with said shelves and through which balls carried by 20 the shelves may be removed, comprising a plurality of substantially parallel cylinders each having one end closed and the opposite end open, said cylinders combining to form a portable unit and being adapted for engagement against the end wall of the rack with the open ends thereof in alignment with adjacent openings of the end wall of the rack and in substantial alignment with the shelves upon which the balls are arranged to thereby permit removal of the balls carried 25 by the shelves through the openings of the end wall into said cylinders for transportation in said cylinders.

2. A pool ball carrier for use in transferring pool balls from wall racks having supporting shelves and an end wall with which the shelves are engaged and which is provided with openings aligned with said shelves and through which balls carried by 30 the shelves may be removed, comprising a plurality of substantially parallel cylinders each having one end closed and the opposite end open, said cylinders combining to form a portable unit and being adapted for engagement against the end wall of the rack with the open ends thereof in alignment with adjacent openings of the end wall of the rack and in substantial alignment with the shelves upon which the balls are arranged to thereby 35 permit removal of the balls carried by the shelves through the openings of the end wall into said cylinders for transportation in said cylinders.

gagement against the end wall of the rack 45 with the open ends thereof in alignment with adjacent openings of the end wall of the rack and in substantial alignment with the shelves upon which the balls are arranged to thereby permit removal of the balls carried 50 by the shelves through the openings of the end wall into said cylinders for transportation in said cylinders, said unit being provided adjacent the open ends of the cylinders thereof with a hand grip, and means 55 carried by the unit for engaging the forearm of the user to support the closed ends of the cylinders.

3. A pool ball carrier for use in transferring pool balls from wall racks having 60 supporting shelves and an end wall with which the shelves are engaged and which is provided with openings aligned with said shelves and through which balls carried by the shelves may be removed, comprising a 65 plurality of substantially parallel cylinders each having one end closed and the opposite end open, said cylinders combining to form a portable unit and being adapted for engagement against the end wall of the rack 70 with the open ends thereof in alignment with adjacent openings of the end wall of the rack and in substantial alignment with the shelves upon which the balls are arranged to thereby 75 permit removal of the balls carried by the shelves through the openings of the end wall into said cylinders for transportation in said cylinders, a hand grip secured to the unit adjacent the open ends of the cylinders 80 thereof, and a member secured to the unit adjacent the closed ends thereof including portions adapted to engage the upper and inner surface of the forearm of the user to thereby support such closed ends.

In testimony whereof I hereunto affix my signature.

RUFUS M. SHERROD.
